UNITED STATES PATENT OFFICE.

FRANK BRAUN AND DWIGHT KIMBLE, OF DECATUR, INDIANA.

DESIGN FOR A CHILD'S ROCKER.

Application filed September 23, 1925. Serial No. 14,885. Term of patent 3½ years.

To all whom it may concern:

Be it known that we, FRANK BRAUN and DWIGHT KIMBLE, citizens of the United States, residing at Decatur, in the county of Adams and State of Indiana, have invented a new, original, and ornamental Design for a Child's Rocker, of which the following is a specification, reference being had to the accompanying drawing, forming part thereof.

The figure is a perspective view of a rocker showing our new design.

We claim:

The ornamental design for a child's rocker, as shown.

FRANK BRAUN.
DWIGHT KIMBLE.
